UNITED STATES PATENT OFFICE.

WILLIAM M. PRICE, OF OSHKOSH, WISCONSIN.

PUMP.

SPECIFICATION forming part of Letters Patent No. 787,308, dated April 11, 1905.

Application filed December 8, 1904. Serial No. 235,986.

To all whom it may concern:

Be it known that I, WILLIAM M. PRICE, a citizen of the United States, residing at Oshkosh, in the county of Winnebago and State 5 of Wisconsin, have invented new and useful Improvements in Pumps, of which the following is a specification.

My invention relates to pumps of the class used in wells.

10 The essential features of my invention are the construction of the supporting-arm and bearing-head in two parts; the construction of the supporting-arm and bearing-head in two parts and bolting the parts together; the 15 construction of the supporting-arm and bearing-head in two parts, the same being provided with an interior annular recess adapted to inclose a corresponding projection upon the pump-head; the construction of the supporting-arm and bearing-head in two parts provided with an interior annular recess adapted to inclose a corresponding projection upon the 20 pump-head, and means for binding the two parts together around the pump-head.

25 My invention consists in certain other new and novel features, which will be hereinafter set forth.

In the accompanying drawings, Figure 1 is a side view of a pump embodying my invention. Fig. 2 is a vertical section of the bearing-head upon the line A A of Fig. 1. Fig. 3 is a front view, Fig. 4 a top view, and Fig. 5 an interior view, of one part of the supporting-arm and bearing-head.

30 Similar numerals refer to similar parts throughout the several views.

2 represents the pump-head provided with an annular projection 3 and a shoulder 4.

5 represents the bearing-head having an annular recess 6 corresponding with the projection 3 and adapted to rest upon the shoulder 4.

40 The bearing-head 5 and supporting-arm 7 are integral with each other and are cast in halves, as shown in Fig. 5, and brought together and secured by nuts and bolts 8 8, passing through the eyes 9 9.

45 This forms a cheap and efficient means of constructing the bearing-head and, further, provides a strong and rigid attachment for the bearing-head to the 50 pump-head. The nuts upon the bolts 8 8 may

be tightened, so as to form an effective bearing entirely around any pump-head.

In pumps heretofore used it has been usual to secure the bearing-head to the pump-head by means of a set-screw. My invention provides a simpler and more secure means of attachment.

The pump-rod 10 slides in the aperture 11 of the supporting-arm 7 and also in a rod-receiving aperture formed in the part 5, which 60 includes the pump-head. The casting of the supporting-arm 7 in two parts obviates the necessity of providing a core for the aperture 11. This simplifies and cheapens the construction. 65

Having thus described my invention, what I claim, and desire to secure by Letters Patent, is—

1. In a pump of the character described, a rod-bearing including a head comprising oppositely-disposed similar contacting sections forming a centrally-disposed rod-receiving aperture therebetween, means for securing the sections together, and a supporting-arm formed of similar sections one section being 70 integral with each head-section, said arm-sections forming a rod-receiving aperture therebetween. 75

2. The combination with a pump-head having an annular projection thereon and an annular shoulder parallel with said projection; of a bearing-head surrounding one end of the pump-head and extending over said end, said bearing-head consisting of oppositely-disposed similar sections bearing on the shoulder 80 and having an interior annular recess engaged by the annular projection on the pump-head. 85

3. The combination with a pump-head having an annular projection and a shoulder; of a bearing-head mounted upon the shoulder 90 and surrounding a portion of the pump-head, said bearing-head consisting of oppositely-disposed similar sections engaging the annular projection on the pump-head and extending from one end of said pump-head, said sections having registering recesses forming a centrally-disposed rod-receiving aperture, and means for binding the bearing-head sections upon the pump-head and its projection. 95

4. The combination with a pump-head hav- 100

ing an annular projection and a shoulder; of a bearing-head mounted upon the shoulder and surrounding a portion of the pump-head, said bearing-head consisting of oppositely-disposed similar sections engaging the annular projection on the pump-head and extending from one end of said pump-head, said sections having registering recesses forming a centrally-disposed rod-receiving aperture, a sectional supporting-arm extending from the bearing-head, the sections of said arm being integral with the respective sections of the

bearing-head and said arms having registering recesses forming a rod-receiving aperture, and means for binding the sections of the bearing-head upon the pump-head and its projection. 15

In testimony whereof I have hereunto set my hand in the presence of two subscribing witnesses.

WILLIAM M. PRICE.
